UNITED STATES PATENT OFFICE.

JOHN W. GURLEY, OF INDIANAPOLIS, INDIANA, ASSIGNOR OF ONE-HALF TO HAROLD TAYLOR, OF INDIANAPOLIS, INDIANA.

FLUID PUMP OR MOTOR.

Application filed July 6, 1926. Serial No. 120,644.

My invention relates to an improved fluid pump or motor which may be utilized for pumping water and other fluids, or as an air compressor, or it may be employed for creating steam motive power, and other purposes, and which is of simple character in construction and operation, small and compact and therefore comparatively inexpensive to manufacture and install, mechanically efficient in its various operating positions, and stable, durable, and positive in operation, as will hereinafter more fully appear.

In the accompanying drawing, forming part hereof, Figure 1 is a vertical sectional view of a pump of the V-type embodying my invention; and Figs. 2 and 3 are vertical sections of a modified form of pump, taken on the dotted lines 2—2 in Fig. 3 and 3—3 in Fig. 2 respectively, the forms illustrated being to show the adaptability of my improvement to different types of pumps, motors, compressors and the like.

In said drawing, the numeral 5 indicates the casing of a pump or power creating apparatus embodying the principle of my invention, said casing being of any preferred form, and in the type shown in Fig. 1 members or casings 6, 7, extend from said main casing 5, in which casing members I mount the cylinders 8, 9, the outer ends of which are secured to the cylinder heads, 10, as by bolts, 11, which heads in turn are connected to the inlet and discharge outlets, 12, 13, respectively. Said casing 5 constitutes a reservoir for containing oil, and, as will be understood, the actuated parts therein and their connections are thoroughly lubricated at all times during the operation of the apparatus. In casing 5 I mount a drive shaft, 15, connected to an eccentric, 16, which is positioned in an eccentric strap, comprising preferably the lower and upper sections, 17, 18, connected by bolts, 19, or otherwise, and extending from said strap is a connecting rod, 20, secured to a pin, 21, mounted in cross-head, 22, in which latter the piston-rod, 23, is connected, as by screw-threading at 24, or otherwise, and which rod passes through a packing gland, 25, supported in casing member 6 by the internal flange 6', to which gland is secured a packing nut, 26, for maintaining packing material 27 in relation to said gland. Piston-rod 23 extends through casing member 6 into intake cylinder 8, and is provided with the piston-head 30, having

openings 31 therethrough, said piston-head being mounted in a suitable packing-ring or rings, 32, in a desired manner, the rod 23 and head 30 being hereinafter referred to as the piston. I provide piston-rod 23 with a valve, 33, slidably and yieldingly supported on said rod by a compression spring, 34, supported by collar, 35, the latter being retained on the rod by pin, 36.

As will be seen, the foregoing description applies to the intake or suction element of my improved apparatus, and the discharge element thereof is to more or less extent a counterpart. However, in carrying out my principle the strap 17, 18, which may if preferred be a single structure, is provided with a bearing, 38, to which is connected, by the pin 39, a connecting-rod, 40, which in turn is connected to pin, 41, in cross-head, 42, in a manner similar to that employed in mounting connecting-rod 20, and to said cross-head 42 I connect a piston-rod, 43, which extends through a packing-nut, 44, and gland, 45, having packing material, 46, therebetween, in a manner substantially as that shown and described with reference to piston-rod 23. The glands 25 and 45 and the packing nuts and packing associated therewith, constituting a unitary bearing for the rods 23 and 43, together with the internal flanges 6' in the casings, form a closure for the casing members 6 and 7, so that a chamber is formed in each, which chambers are connected by a conduit or conductor 60 for the conveyance of fluid from the intake to the discharge cylinders, as will further appear. The cross-heads 22 and 42 may be packed by any suitable material, such as felt or the like, which will absorb oil carried from the reservoir for lubrication and at the same time prevent the passage of surplus water into the reservoir. At the outer end of piston-rod 43 I mount an open piston-head, 48, similar to piston-head 30, and which is provided with packing-rings, 49. In contradistinction to piston 30, I mount a valve, 52, on piston-rod 43 at the outer side of the piston-head 48, which is yieldingly positioned on said rod by the compression spring, 53, secured on the rod by a nut, 54, or otherwise. It will thus be seen that the valves 33 and 52 on the piston-rods 23 and 43 are respectively on the inner side of piston 30 and on the outer side of piston 48. Beneath the packing glands 25 and 45 in each cas-

ing member 6 and 7 I provide an opening or chamber, 56, for access to the packing nuts and associated parts.

From the foregoing it will be understood that I provide a suction or intake element for the fluid or liquid employed and an outlet element for the discharge of such fluid or liquid, and connect such elements by the conduit or conductor, 60, in a manner that the oncoming fluid drawn through the inlet 12 will be continuously conveyed to the outlet 13 during the operation of my improved apparatus, which is as follows:

It will be understood that according to the character of the work to be performed by my improved apparatus the same may be positioned either vertically as shown or otherwise, and actuated by manual or mechanical power imparted to shaft 15, that is to say, when devised, for example, as a milk pump for use at refreshment stands and the like, the apparatus may be manually operated, and when greater service is required, such as the pumping of water in large volume, or steam for motive power, eccentric 16 may be mechanically driven. When said shaft 15 is actuated the relative eccentric relation thereof to the ring 16 and strap 18 causes the throw of said shaft to double the throw of piston 30 per each revolution of such shaft, so that in the reciprocal travel of the piston 30 above and below center the throw thereof is twice that of the throw of said eccentric, and likewise through the longer compensatory travel of rod 40 connected to piston-rod 43 a similar result is effected, in the travel of piston 48, that is, the piston 43 is also caused to travel twice the distance per revolution of shaft 15, so that in the reciprocal movements of the pistons 30 and 48 the stroke of each is twice that of the throw of said eccentric 16, and by which assemblage and connections I am enabled to obtain four times the travel of the pistons from the throw of the eccentric in comparison with one-half such power obtained in pumps and similar apparatus of which I am aware. During such operation it will be understood that I employ the counterbalance 61, which is of approximately the same weight as the connecting rods and parts associated therewith, in order to maintain the equilibrium of the driving parts at constant speed, which, of course, is a common and well known expedient for the purpose.

As is well known to those skilled in such matters, the standard of speed of reciprocating pumps in general is approximately one hundred feet piston travel per minute, but by my improved apparatus I am enabled to reciprocate the pistons at materially higher speed than standard and thereby greatly increasing its volume, and thus synchronize the action of the valves with the speed of the fluid so that as the valves are closing

water-hammer is eliminated, as the continuous flow of the fluid is never interrupted or stopped for the reason that the valves are at no time closed against the fluid during its circulation. As shown in Fig. 1, piston 48 is on its upward stroke, the valve 52 being closed and raising the pressure of the fluid in outlet 13, and which action of said parts is at the same time creating a vacuum in conductor 60 and the chambers communicating therewith, which draws the fluid into said conductor, and during which operation valve 33 is opened. During this period the eccentric 16 is at a quarter turn upward, and when said eccentric strikes dead center the pistons momentarily stop, at which particular moment the circulating fluid, traveling faster than the pistons, opens both of said valves. At this instant the pistons are starting on the downward stroke, and the eccentric rotates from dead center with a slow vertical movement due to the fact that the valves are open and the fluid is consequently traveling faster than the pistons, during which occurrence the pressure is being raised in conductor 60 and creating a vacuum in inlet 12 which opens the valve 52, and vice versa, so that in the reciprocal action of said pistons there is a constant flow of fluid into the inlet through the conduit or conductor, and out through the discharge of the cylinder 9. Such flow is constant and unobstructed for the reason that the yielding valves 33 and 52, as stated, are never sufficiently closed against the passage of fluid as to prevent the pressure thereof from opening such valves, and the suctional power of piston 30 and discharge power of piston 48 insure a siphon-like continuous circulation of the fluid at all times without disturbance of the assembled mechanisms or the common water-hammer incident to the operation of pumps and the like; in other words, the fluid passing through the intake cylinder, through the conduit, and thence outwardly through the discharge cylinder, and displacing the valves in its passage, causes such fluid to travel continuously and uninterruptedly, its travel being accelerated by the reciprocation of the pistons, the valves of which synchronize with the speed of the fluid, and which pistons are required to travel but a very short distance, as indicated in the drawing. By the synchronizing action of the valves with the flow of the fluid a high rate of speed of the pistons is attained, by which the inertia of the fluid is overcome, for the reason that the fluid at all times flows uninterruptedly through the valves, and with such high speed and the valves working continuously and alternately on the fluid (one valve taking up the fluid as it is leaving the other valve), a high rate of continuous and uninterrupted flow of the fluid is produced, which, as stated, over-

comes its inertia, so that in actual practice I have demonstrated that my improved pump, of large or small capacity, when mechanically driven, produces a siphon-like continuous and incessant circulation of the fluid, and at all times continuously functions in the manner stated, and without the water-hammer or pulsations commonly present in pumps where such action of the fluid is not attained.

5 And in overcoming the inertia of the fluid, as indicated, which is not accomplished by pumps with which I am aware, I provide a highly practical and efficient apparatus of the kind for general purposes. It will be

10 further understood that the principle involved in the apparatus shown and described may be utilized for a gas engine and other purposes, as the mechanisms therein require but slight modification in minor details, such

15 as packing and the like, and that for use as a hydraulic pump, or a pump for heating systems and the like, the apparatus may be made on a comparatively small or large scale and the intake and discharge elements multiplied according to the service required.

In Figs. 2 and 3, as stated, a modified form of my improvement is disclosed, which to all intents and purposes is substantially the same in construction and operation as that shown in Fig. 1, except that the piston rods are remotely connected to an eccentric or crank-shaft as may be desired, and that the position of the intake and compression cylinders has been reversed as indicated by the arrows in Fig. 2. It will be understood that the arrangement and operation of the valves in a pump or similar apparatus produce an extremely simple double-acting pump by the alternating action of the pistons which create a continuous flow of fluid without loss of energy, as all of the energy is maintained in the water (less skin friction) due to the fact that there is no obstruction to the flow and that when the water travels slower than the pistons the latter pick up and propel the water in such continuous flow.

In the simple manner described I produce a practical double-acting pump embodying two valves only, in contra-distinction to pumps of this character which require at least four valves, and in many instances eight valves are employed, and in overcoming the fluid inertia as stated, and maintaining constant and uninterrupted flow of the fluid, my simple pump or similar apparatus of a given size is capable of greater capacity than practical pumps of the same size of which I am aware. And also, as indicated in Fig. 1, it will be apparent that in the reciprocation of the pistons an angular relation exists between the rods 40 and 20, and during such reciprocation of the rods about rotating shaft 15 there is a pronounced variation in their respective strokes,

that is to say, the timing of rod 40 is in advance of rod 20, and therefore an overlapping of the stroke of rod 40 in relation to the stroke of rod 20, with the result that there is a pick-up by said rod 40 during 70 the coincident reciprocation of said rods, as the load of rod 20 is synchronously transmitted to the reciprocating action of rod 40, and therefore a continuous transference or pick-up of the load is established during 75 the reciprocation of the intake and discharge piston rods whereby such continuous and uninterrupted flow of the fluid through the intake and thence outwardly through the discharge cylinders is created without permitting any momentary lack of inactivity or sluggishness of the fluid, or, in other words, there is an entire absence of inertia of the fluid, as the reciprocal action of the intake and discharge pistons due to the compensatory rod 40, through its overlapping stroke in relation to the stroke of rod 20, is an absolute preventive of such situation, and a continuous powerful flow of fluid is produced.

90 I claim as my invention:

1. In an apparatus of the class described, a cylinder, a piston therein embodying an open head and a rod, a valve adjacent the inner side of said head, yielding means for forcing said valve toward said head, a cross-head to which said rod is connected, means for reciprocating said piston, a discharge cylinder, a piston therein embodying a rod, a cross-head to which said rod is connected, a compensatory rod connecting said cross-head and said reciprocating means said piston having an open head, a valve on the outer side of said head, yielding means for forcing said valve towards said head, and means for actuating said reciprocating means to operate said pistons.

2. In an apparatus of the class described, a casing, an intake cylinder in said casing, a piston therein for drawing fluid into said cylinder, a valve associated with said piston and displaceable by said fluid, a discharge cylinder in said casing, a piston therein for forcing fluid therefrom, a valve on said latter piston displaceable by fluid pressure, a conductor connecting said cylinders substantially at the point of limit of the inward stroke of said pistons, for conveying fluid from the intake to the discharge cylinders, and means for reciprocating said pistons simultaneously in outward and inward directions to draw fluid through said intake cylinder into said conductor and through said discharge cylinder in a continuous flow.

3. In an apparatus of the class described, a casing, driving mechanism enclosed in said casing, means for driving said mechanism, a connecting rod extending from said driving mechanism, a cross-head secured to said

- 4
- rod, a piston-rod attached to said cross-head and having a piston at its outer end, a bearing in said casing in which said rod is mounted to reciprocate said bearing forming the lower portion of a chamber in said casing, a yieldingly mounted valve on said rod, an open-ended intake cylinder in which said piston is mounted; a discharge cylinder in said casing; a piston-rod in said discharge cylinder having a piston mounted thereon, a connecting-rod secured to said driving mechanism and pivotally secured to said latter piston-rod, a bearing in which said latter piston-rod is mounted to reciprocate, said bearing forming the lower portion of a fluid containing chamber in said casing, a yieldingly mounted valve on said rod; and a conduit connecting said cylinders at approximately the point of limit of the inward stroke of said pistons for conducting fluid from said intake to said discharge cylinders.
5. In an apparatus of the class described, a casing, an eccentric driving mechanism therein, a fluid intake piston connected to said driving mechanism, a cylinder embodying a chamber in which said piston reciprocates, a discharge piston connected to said driving mechanism, a cylinder embodying a chamber in which said discharge piston reciprocates, a conductor connected to said chambers, and means for actuating said driving mechanism to simultaneously reciprocate said pistons in the same direction to induce the flow of fluid through said intake cylinder and from thence through said conductor to said discharge cylinder to be conveyed therefrom.
6. In an apparatus of the class described, a casing, a plurality of cylinders, in said casing, reciprocating pistons therein, valves associated with said pistons, a conductor connecting said cylinders approximately at a point reached by the inward stroke of said pistons, and means to which said pistons are connected for simultaneously reciprocating said pistons in the same direction.
7. In an apparatus of the class described, a main casing embodying an oil reservoir, cylinder casings connected to said main casing and having openings therein, driving mechanism in said main casing and associated with said cylinder casings, pistons in said casings connected to and actuated by said driving mechanism, bearings in said casings accessible for adjustment through said open-ings, a conductor connecting said cylinder casings substantially at the point of limit of the inward stroke of said pistons, and means for actuating said driving mechanism for circulating fluid from one of said cylinder casings and through said conductor to the other of said cylinder casings in the manner substantially as set forth.
8. In an apparatus of the class described, a casing, a fluid intake cylinder, a piston in said cylinder, driving mechanism in said casing, a rod connecting said piston and driving mechanism, a discharge cylinder, a piston in said discharge cylinder, a cross-head, a rod connecting said latter piston and cross-head, and a compensatory rod connecting said cross-head and said driving mechanism the stroke of said compensatory rod being in advance of the stroke of the rod connecting the driving mechanism to the piston in the intake cylinder whereby inertia of the fluid passing through the apparatus is overcome.
9. In an apparatus of the class described, a casing embodying intake and discharge cylinders, a piston in said intake cylinder, a cross-head connected to said piston, a driving shaft in said casing, a driving rod connected to said cross-head and eccentrically mounted on said shaft, a piston in said discharge cylinder, a cross-head connected thereto, a connecting rod pivotally secured to said cross head, the stroke of said connecting rod being in advance of the stroke of said driving rod whereby the load of the latter is continuously relieved and received by said connecting rod and inertia of the fluid passing through said apparatus thus overcome.
10. In an apparatus of the class described, a casing embodying intake and discharge cylinders; pistons in said cylinders; cross-heads in said casing; rods connecting said pistons and cross-heads; an eccentrically mounted driving element in said casing; a rod connecting said element to the intake piston cross-head; a rod pivotally secured to said element and also pivotally secured to the discharge piston cross-head, the length of stroke of the latter rod being in advance of the stroke of the rod connected to the intake piston cross-head; and means for driving said eccentric element to reciprocate said connecting rods and the pistons associated therewith whereby the load of the intake piston connecting-rod is uninterruptedly transferred to the stroke of the discharge piston connecting-rod for overcoming inertia of the fluid passing through said apparatus.
11. In an apparatus of the class described, a casing embodying intake and discharge cylinders; pistons in said cylinders; cross-heads in said casing; rods connecting said pistons and cross-heads; an eccentrically

mounted driven element in said casing; a rod connecting said element to the intake piston cross-head; a rod pivotally secured to said element and also pivotally secured to the discharge piston cross-head the length of stroke of the latter rod being in advance of the stroke of the rod connected to the intake piston cross-head a fluid conductor connecting said cylinders at substantially the point of the inward stroke of the pistons therein;

and means for driving said eccentric element to reciprocate said connecting rods and the pistons associated therewith whereby the load of the intake piston connecting-rod is uninterruptedly transferred to the stroke of ¹⁵ the discharge piston connecting-rod for overcoming inertia of the fluid passing through said apparatus.

In testimony whereof I affix my signature.
JOHN W. GURLEY.
